H. R. PATTERSON

IGNITION COIL

Filed Dec. 26, 1919

INVENTOR.
Harry R. Patterson
BY *Chester W. Braselton*
ATTORNEY

UNITED STATES PATENT OFFICE.

HARRY R. PATTERSON, OF TOLEDO, OHIO, ASSIGNOR TO THE ELECTRIC AUTO-LITE COMPANY, OF TOLEDO, OHIO, A CORPORATION OF OHIO.

IGNITION COIL.

Application filed December 26, 1919. Serial No. 347,593.

To all whom it may concern:

Be it known that I, HARRY R. PATTERSON, a citizen of the United States, residing at Toledo, in the county of Lucas and State of Ohio, have invented certain new and useful Improvements in Ignition Coils, of which I declare the following to be a full, clear, and exact description.

This invention relates to induction coils of 10 that type which is particularly adapted for use in ignition systems for internal combustion engines.

An object of my invention is to provide an improved housing in which the coil may be 15 mounted and which shall completely enclose the coil protecting it from dirt, water and oil, as well as from physical injury.

A further object is to construct such a 20 housing in part of a paramagnetic material which shall afford a partial return path for the lines of force produced by the coil and which shall be of a form that eddy currents therein are restricted.

Further objects of this invention relate to 25 economies of manufacture and details of construction as will hereinafter appear from the detailed description to follow. I accomplish the objects of my invention in certain instances by the devices and means described in the following specification, but it is evident that the same may be varied widely without departing from the scope of the invention, as pointed out in the appended claims. Structures constituting certain embodiments of my invention, any one of which may be the preferred, are illustrated in the accompanying drawings forming a part hereof, in which:

Figure I is an end elevation of an induction coil illustrating my invention.

Fig. II is a longitudinal vertical sectional view thereof.

Fig. III is a transverse sectional view taken midway of the coil.

Figs. IV, V and VI are respectively, an end elevation, a longitudinal sectional view and a transverse sectional view corresponding to Figs. I, II and III but illustrating a modification and

Fig. VII is a circuit diagram.

In the drawings, the same reference numerals refer to similar parts throughout the several views,

Referring first to the modification shown in Figs. I, II and III, the coil proper comprises a core 5 shown in this instance as constructed by rolling up a length of sheet iron, a primary winding 6 surrounding the said core and insulated from it and a secondary winding 7 surrounding and insulated from the primary winding 6. The coil thus formed is surrounded by suitable insulation and the ends may be enclosed as shown by two heads 8 of suitable insulating material.

An enclosing casing for the coil is formed in part of two end heads 9 of suitable insulating material, one of which is shown provided with lugs 10 associated with terminal posts 11 for facilitating the attachment of terminals 12. Each head 9 has a groove 13 on its inner face and engaging in this groove are the ends of a casing member 14 of magnetic material which, as shown in Fig. III, extends partially around the coil, the gap between its adjacent sides being completed by a plate 15 of non-conducting material. This member 15 is suitably secured to the magnetic member 14, as by rivets and also extends into the grooves formed in the inner faces of the end heads 9. A bolt 17 is shown extending through the core 5 and the two end heads 9 and provided with a nut 18 at each end by means of which the two heads may be clamped against the coil and the casing member 14 and a plate 15. A completely closed, water and oil tight casing is thereby obtained. By constructing the member 14 of the casing of magnetic material as for example sheet steel, the casing

is not only rendered firm and rigid but an increased efficiency of the coil follows from the fact that a partial return magnetic path is thereby provided for the core flux. By this construction, the entire primary flux interlinks the entire secondary winding. Eddy current flow is effectively prevented by the gap spanned by the plate 15. Mounted upon the plate 15 is the high ten-

2
sion terminal 20 which is connected to one end of the secondary winding 6 by a wire not shown while the opposite end is grounded on the casing 14. The terminal 20 is shown secured in place by a washer 21 and the distance between the washer and an adjacent edge of the casing 14 may be so constructed that a spark will jump thereover before breaking down the insulation within the coil, being in effect a safety spark gap. The casing member 14 as shown in Fig. III, is constructed with a square base portion upon which is mounted the condenser 23 suitably secured in place by a plate 24 having ears 25 extending through and clinched against the under side of the base portion. A mounting bracket 27 is shown attached to the same base portion. Suitable electrical connections are made between the windings, the condenser and the terminal posts which are well known and similar to those of coils in common use and therefore do not require detailed description herein.

The modification illustrated by Figs. IV, V and VI is similar to that previously described with the exception that the magnetic casing 14' is of cylindrical form and the end heads 9' are of circular form to correspond therewith. The condenser 23' is curved to conform to the cylindrical casing and is mounted within the same in substantially the same manner as previously described. The supporting bracket 27' is also suitably modified in shape to fit the casing. In this modification the arrangement of primary winding 6' and secondary winding 7' is shown reversed to that of the form previously described. Although the two windings function in substantially the same manner in either arrangement, in certain cases, as for example where a higher resistance primary is desirable or where it is necessary to provide for a more rapid dissipation of heat from the primary winding, this winding may be wound outside of instead of within the secondary winding.

In the circuit diagram forming Fig. VII, the induction coil is shown, by way of example only, as having its primary connected in a system including a third brush generator 30, an interrupter 31, a storage battery 32 and a lighting circuit 33. In such a system the coil is adapted to supply the ignition spark for an internal combustion engine driving the generator.

While I have described my invention in more or less detail, and as being embodied in certain precise forms I do not desire or intend to be limited thereto, as on the contrary my invention contemplates broadly all proper changes, as well as the omission of immaterial elements and the substitution of equivalents therefore, as circumstances may suggest or necessity render expedient.

Having thus described my invention, what I claim as new and desire to secure by Letters Patent, is:

1. In a device of the class described the combination of a core, a primary winding and a secondary winding wound thereon, a casing for said core and windings, comprising a member of magnetic material extending approximately around the same, a member of non-conducting material joining the adjacent ends of said casing and a high tension terminal carried by said non-conducting member.

2. In a device of the class described, the combination with a core, a primary winding and a secondary winding surrounding said core of an end head at each end of said core, an intermediate member of magnetic material nearly surrounding said core and winding and whose opposite ends engage said end heads, a member of non-conducting material extending between the said heads and closing the space between the adjacent sides of said intermediate member, and a terminal for the secondary winding mounted on said non-conducting member.

3. In a device of the class described, the combination with an induction coil comprising a core having primary and secondary windings inductively related thereto, of a housing for said coil comprising a pair of spaced end heads and an intermediate surrounding portion engaging said heads formed in part of a member of magnetic material and in part of a member of non-conducting material whose ends are secured to the ends of said magnetic member and means for securing said induction coil within said housing.

4. In a device of the class described, the combination of a core, primary and secondary windings thereon, an end head adjacent each end of said core, a sheet steel member engaging said heads and bent to extend about said core and windings, a plate of insulating material secured to the adjacent edges of said member and also engaging said heads and a high tension terminal carried by said plate and spaced from said edges.

5. In a device of the class described, the combination of a core having primary and secondary windings thereon, means for housing said core and windings and for partially completing the magnetic circuit of said windings, said means having a gap extending longitudinally of said core and non-conducting means for bridging said gap and supporting a terminal of said secondary winding.

6. In a device of the class described, the combination of a core, primary and secondary windings thereon, an end head adjacent each end of said core, a sheet steel mem-

ber engaging said heads and bent to partially surround said core and windings, a plate of insulating material secured to the adjacent edges of said member to thereby completely enclose said coil and windings, a high tension terminal secured to said plate and connected with said secondary winding, a condenser mounted on the inner face of said member, a supporting bracket secured to said member and means for 10 clamping said end heads to said core, said member and said plate.

In testimony whereof, I affix my signature.

HARRY R. PATTERSON.
